CLOCK CASING

Monte L. Levin, New York, N.Y., assignor to General
Time Corporation, Stamford, Conn., a corporation of
Delaware

Filed Oct. 17, 1967, Ser. No. 9,027

Term of patent 14 years

(Cl. D42—7)

FIG. 1

Des. 212,026

PAGE 2

FIG.2

FIG.4

FIG.3

FIG. 1 is a front elevational view of a clock casing showing my new design;

FIG. 2 is a rear elevational view;

FIG. 3 is a top plan view; and

FIG. 4 is a right side elevational view.

The essential features of my design for a clock casing are shown in the full line portions thereof, while the clock face and hands, shown in broken lines in FIG. 1, are for illustrative purposes only.

I claim:

The ornamental design for a clock casing, substantially as shown and described.
